DESIGN FOR A BUILDING SIDING UNIT OR THE LIKE

Walter J. Heinning, Buffalo, N. Y.

Application January 11, 1945, Serial No. 117,374

Term of patent 14 years

(Cl. D68—1)

To all whom it may concern:

Be it known that I, Walter J. Heinning, a citizen of the United States, residing at Buffalo, in the county of Erie and State of New York, have invented a new, original, and ornamental Design for a Building Siding Unit or the like, of which the following is a specification, reference being had to the accompanying drawing, forming part thereof.

In the accompanying drawing:

Fig. 1 is a perspective view of a building siding unit or the like showing my new design.

Fig. 2 is a top plan view thereof.

Fig. 3 is a view from the front edge thereof.

Fig. 4 is a view from the side edge of the same.

I claim:

The ornamental design for a building siding unit or the like, as shown.

WALTER J. HEINNING.
